US00D862899S

(12) **United States Design Patent** (10) **Patent No.:** **US D862,899 S**
(45) **Date of Patent:** **** Oct. 15, 2019**

(54) **LINT ROLLER IN OPEN POSITION**

(71) Applicant: **3M INNOVATIVE PROPERTIES COMPANY**, St. Paul, MN (US)

(72) Inventors: **Lloyd S. Vasilakes**, Stillwater, MN (US); **Mark W. Baldwin**, Woodbury, MN (US)

(73) Assignee: **3M INNOVATIVE PROPERTIES COMPANY**, St. Paul, MN (US)

(**) Term: **15 Years**

(21) Appl. No.: **29/648,801**

(22) Filed: **May 24, 2018**

(51) **LOC (12) Cl.** **04-01**

(52) **U.S. Cl.**
